3 SHEETS—SHEET 3.

UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

FEED STOP.

Application filed November 19, 1919. Serial No. 339,100.

To all whom it may concern:

Be it known that I, RICHARD LESTER WILCOX, a citizen of the United States, residing at Waterbury, in the county of New Haven and State of Connecticut, have invented certain new and useful Improvements in Feed Stops, of which the following is a specification, reference being had therein to the accompanying drawings.

10 This invention relates to new and useful improvements in feed stops having particular reference to mechanism for limiting the extent of movement of a length of metal, or other material, being moved either manually or by mechanical means; so as to determine one dimension of a blank to be cut therefrom.

As herein shown and illustrated I have applied my invention to an upsetting machine, 20 that is, a machine where the blanks after being cut from a length are upset, either throughout their entire length or only a portion thereof.

It is the object of this invention, among 25 other things, to provide a feed stop that will have a movement variable in length, parallel with the path of travel of the material in the machine, which may be given a circular movement in relation thereto if desired, its position in relation to other mechanism of the machine varied, or it may be so controlled as to occupy a fixed position.

Aside from these, and other desirable 35 objects, such as simplicity and compactness of structure, ease of adjustment, etc. it is so designed that the source of power for its operation is derived from other movable parts of the machine that are essential to 40 the operation thereof.

To these, and other ends, my invention consists in the feed stop having certain details of construction and combinations of parts, as will be hereinafter described, and 45 more particularly pointed out in the claims.

Referring to the drawings, in which like numerals of reference designate like parts in the several figures;

Figure 1 is a fragmentary plan view of 50 a portion of an upsetting machine with my improved mechanism shown in connection therewith;

Figure 2 is a fragmentary side elevation

of the parts as shown in Figure 1 with the cam and adjacent elements shown in such 55 position as will impart the maximum parallel motion to the feed stop;

Figure 3 is a side elevation of a portion of my improved mechanism illustrating the relative position of the cam and its adjacent elements whereby the length of the movement of the feed stop is between its maximum and minimum;

Figure 4 is a similar view with the feed stop held against endwise movement; and 65

Figure 5 is an enlarged sectional view of the slide block and adjacent parts, taken upon line 5—5 of Figure 1.

In upsetting machines, sometimes known as heading machines, a wire rod is either 70 automatically or manually fed into the machine, a length, generally described as a blank, cut therefrom, which is then moved into line with the upsetting mechanism, if not already there and subjected to pressure 75 in or between dies one usually being stationary and the other movable. This pressure upsets the blank in the desired manner after which it is ejected from the machine. Mechanism of this type is well known in the 80 art and therefore I have only shown so much thereof as is essential to a clear understanding of my invention.

In the drawings, the numeral 10 designates the bed of the machine supported upon 85 suitable legs 24, in which is secured a die holder 11 having a stationary die 12 therein; 13 is the gate which has a reciprocating movement in the body 10 toward and away from the die holder 11 and fixed 90 on the forward end of which is the die holder 14 carrying a punch 15 therein. The punch 15 and the stationary die 12 have formed in their meeting faces recesses or depressions to accommodate the flow of the 95 metal during its pressure therebetween, and in the machine illustrated these recesses are semi-circular as at 16 so that when the faces thereof are in contact with each other the metal blank therebetween will be formed 100 into a ball. It will be understood, however, that this shape and form is merely for the purpose of illustration as such recesses may be so shaped as to form a head upon a blank, or the blank upset in many other 105 ways.

Mounted on a rotating shaft 17 is a cam 18, which in some types of machine, is a spur gear, the face of the gear being utilized to form the cam.

5 The wire rod 19 is fed, either manually or by mechanism into the machine in the feed line designated 20 so that the inner end thereof projects in front of a line across the face of the die 12, at which time the 10 knife 21 on the end of the cut-off bar 22 which moves in a path at right angles to the line of wire feed, cuts off the projecting portion of the wire, forms a blank therefrom which is transferred to the upsetting 15 line, designated 23 and is there held until the gate moves forward and the blank is engaged by the die 12 and punch 15 at which time the cutter bar 22 and knife 21 are withdrawn and the blank acted upon 20 by said punch and die.

All of the mechanisms above described are old in the art and constitute no part of my present invention which relates particularly to the mechanism for limiting the feed 25 of the wire so as to determine the length of the blank that is to be severed therefrom by the knife 21.

One function of my invention is to automatically move the feed stop toward and 30 away from the plane of the face of the die 12 so as to allow the cut off bar 22, which holds the knife, to advance and cut off the required length therefrom to form the blank and carry it over to the upsetting line, with 35 out interfering with the feed stop.

In certain lengths of blanks it is not necessary that motion should be given to the feed stop, as there is ample room for the knife 21 and bar 22 to clear the feed stop.

40 This, however, is not true if the blank is comparatively short because if the feed stop is not movable away from the end of the wire, the cut-off bar would have to be reduced to such size as to clear the feed stop 45 and in doing this it will become so weakened as not to stand the requisite strain and pressure to cut off the blank. Therefore, I have provided a feed stop that will permit the finger thereon to move toward and away 50 from the plane of the face of the die 12 to a predetermined position for the wire to be fed against it, and then before the blank is severed therefrom, moved away a sufficient distance to allow the cutter bar to pass in 55 front thereof. I have provided means whereby the extent of this movement of the feed stop finger may be varied or it may be held against relative movement and can be moved in a circular path for the purposes 60 hereafter described.

Fixed in one end of the body 10 are the studs 25 upon which is mounted a slide 26 which has a movement toward and away from said body, and threadably mounted 65 therein is an adjusting sleeve 27.

Supported near one end by the bushing 28 in the body 10 and near the other end in the sleeve 27, is the shaft 29 having fixed on its inner end the finger stop 30 preferably provided with a hardened button 31, the axis 70 of which button is normally coincident with that of the feed line 20.

A nut 32 on the end of the shaft 29 contacts with one face of the finger 30 and prevents endwise movement thereof upon said 75 shaft.

On the end of the shaft 29 opposite the finger 30 is a link block 33, to which a handle 35 is pivotally connected by the stud 34, and against which bears the free end of 80 the spring 36, which is also mounted upon the shaft 29, and held against relative movement in relation to the block 33 by the dowel pin 37. Both the block 33 and spring 36 are held against endwise movement on the shaft 85 by the nut 38 threaded thereon.

Adjustably secured to the slide 26 by the bolts 39 is a lock plate 40 having two notches 41 and 42 in its outer end, the former of said notches being slightly deeper than the latter. 90

When the axis of the button 31 is coincident with the wire line 20, the handle 35 is held in the notch 41 by the spring 36 so that no rotary movement can be imparted to the finger 30, but if it is desired to move said finger in a circular path, the handle 35 is rotated upon its pivot mounting 34 against the pressure of the spring 36 and the shaft is then rotated until the handle 35 is moved into the recess 42 where it is then again held 100 against movement by pressure of the spring 36. Ordinarily this rotary movement of the finger is not required but for the purpose of adjustment of mechanisms and for manual feeding, it is desirable and is especially ad- 105 vantageous for purposes of ejecting the short end of the rod just before a new rod is presented. If the last end of the wire does not furnish sufficient metal for a full length blank it is preferable that this short end be 110 ejected, otherwise it is liable to break either the knife or dies and in any case will produce an imperfect product. With a feed stop that cannot be moved out of the path of the wire feed it is impossible to eject this short 115 end. Now, by the means herein provided, when the end of the wire rod is about to be presented to the cut-off knife the operator stops the machine, swings the feed stop through manipulation of the handle 35 out 120 of the path of the wire feed, moves the rod manually sufficiently to eject the short end of the previous rod, then returns the finger to its operative position, brings the end of the wire against the button 31, and then 125 starts the machine with a blank of the proper length whereby all danger of breaking the parts is eliminated.

Secured to the body adjacent to the studs 25 is the bracket 43 within which is mounted 130

the rock shaft 44, having fixed on one end thereof the lever 45 and on the other end the cam 46. Motion is imparted to said rock shaft 44 from the cam 18 through the rock lever 47, which is rotatably mounted upon a stud 48 fixed in the bed 10 having a cam roll 49 upon one arm thereof which lies within the groove 50 of the cam 18 and imparts motion to the rock lever 47, which is transmitted to the lever 45 through the rod 51, which is joined to the lever 47 by the connection 52, and to the lever 45 by the swivel block 53, pivotally connected to said lever.

The rod 51 is threaded into the connection 52 and locked therein by the nut 54 and is provided near its opposite end with the nuts 55 which are threaded thereon and engage the opposite faces of the swivel blocks 53.

Rotatably mounted upon studs 56 fixed in the slide 26 are the cam rolls 57 which engage the operative face of the cam 46 and by reason thereof transmit a reciprocating motion to the slide 26 toward and away from the bed 10 and carrying with it the shaft 29, this motion providing the parallel movement of the shaft 29 and the movement of the finger 30 toward and away from the plane of the face of the die 12.

The periphery of the cam 46 is constructed with two concentric portions 58 and 59, the former having a greater radius than the latter and these two concentric portions being connected by the curved faces 60. The relative position of this cam about the axis 35 of the shaft 44 determines the length of the parallel movement of the finger 30 or whether it has any parallel movement at all, and this radial position is in turn determined by the relative position of the outer 40 end of the lever 45 with the connection 43, this adjustment being obtained through the manipulation of the nuts 55 whereby the swivel block 53 is caused to move along the said rod 51, so that it will be moved into 45 and held against movement in its adjusted positions. Three of the relative positions of the cam 46 are shown in Figures 2, 3 and 4 of the drawings.

In Figure 2, the maximum parallel motion 50 will be given to the finger because the cam rolls 57 ride from the high portion 58 to the low portion 59 of said cam thereby obtaining the extreme movement thereof.

In Figure 3 a considerably shorter parallel movement is derived by reason of the fact that said cam rolls do not ride from the high to the low portions of said cam, the movement of said cam being such that this is not possible. While in Figure 4 one of 60 the cam rolls is always in contact with the high portion 58 of the cam and the other with the low portion 59 thereof so that no parallel motion whatever is imparted to the finger 30.

The two extreme positions of the cam 46 and lever 45 in each of these views is shown, one by full lines and the other by broken lines.

There are minor changes and alterations that can be made within my invention, aside from those herein suggested, and I would therefore have it understood that I do not limit myself to the exact construction herein shown and described, but claim all that falls fairly within the spirit and scope of my invention.

Having described my invention, what I claim as new and desire to secure by Letters Patent, is:

1. In a mechanism of the character described, wherein material is fed therein at one place, pieces successively cut from the end thereof and the cut pieces transferred to another place, the combination therewith of means for limiting the movement of said material at its feed in line while the cut off and transfer mechanisms are withdrawn, comprising an element movable in a line substantially parallel with the path of movement of said material and in timed relation with said cut off and transfer mechanisms, said feed limiting means being stationary in the stop position at the time the material is brought into contact therewith.

2. In a header or upsetting machine wherein the material to be operated upon is fed therein at one place, pieces successively cut from the end thereof and the cut pieces transferred to another place, the combination therewith of means for limiting the feed movement of said material at its feed in line while the cut off and transfer mechanisms are withdrawn, comprising an element movable in a line substantially parallel with the path of movement of said material and in timed relation with said cut off and transfer mechanisms, and means for varying the length of said parallel movement.

3. In a mechanism of the character described, wherein material is fed therein and pieces successively cut from the end thereof, the combination therewith of means for limiting the feed movement of said material while the cut off mechanism is withdrawn, comprising an element movable in a line substantially parallel with the path of movement of said material; and means whereby the length of said parallel motion may be varied or said element held in a fixed position.

4. In a mechanism of the character described, the combination with a stop for limiting the movement of material therein; of means for moving said stop into and out of its stop position between successive feeding movements of said material, said means being actuated through a cam; and means

for adjusting the relative position of said cam so as to vary the extent of movement of said stop means.

5. In mechanism of the character described, the combination with a stop for limiting the movement of material therein; of means for moving said stop into and out of its stop position between successive feeding movements of said material, said means being actuated through a cam; and means for adjusting the relative position of said cam so as to vary the extent of movement of said stop means, or to hold the same against movement.

15 6. In a device of the character described, the combination with a feed stop for limiting the movement of material therein; of means for imparting a reciprocatory movement thereto, said means comprising a rock member; a cam connected with said rock member; means for actuating said rock member; an operative connection between said cam and said feed stop; and means for varying the operative position of said 25 rock member about its axis so as to impart a stroke of variable length to said feed stop.

7. In a device of the character described, the combination with a stop finger; of a shaft connected therewith; a member connected with said shaft; and means for reciprocating said member, said means comprising a cam having an operative connection with parts on said member; means for imparting movement to said cam; and means for adjusting the relative positions of said shaft and member.

8. In a device of the character described, the combination with a stop element; of a shaft connected therewith; a slide connected 40 with said shaft; means for varying the rotative positions of said shaft and slide; a rock member mounted upon a member independent of said member and slide; a cam connected with said rock member having engagement with parts upon said slide so that movement will be imparted to said slide; and means for actuating said rock member.

9. In a device of the character described, the combination with a stop member to limit 50 the feed movement of material therein; of means for imparting a reciprocatory movement thereto, said means comprising a slide, a rock member mounted upon a part independent of said slide, a cam connected with 55 said rock member, and elements connected with said slide and having contact with said cam; and means for varying the relative position of said cam and elements.

10. In a device of the character described, 60 the combination with a stop member to limit the feed movement of material therein; of means for imparting a reciprocatory movement thereto, said means comprising a slide, a rock member mounted upon a part inde-

pendent of said slide, a cam connected with 65 said rock member, and elements connected with said slide and having contact with said cam, means for varying the relative position of said cam and elements; and means connected with said stop member for rotating the same in relation to said slide.

11. In a device of the character described, the combination with a stop member to limit the feed movement of material therein; of means for imparting a reciprocatory movement thereto, said means comprising a slide, 75 a rock member mounted upon a part independent of said slide, a cam connected with said rock member, and elements connected with said slide and having contact with 80 said cam; means for varying the relative position of said cam and elements; means connected with said stop member for rotating the same in relation to said slide; and means for holding said stop member against 85 accidental movement in its extreme rotary positions.

12. In a device of the character described, the combination with a stop member to limit the feed movement of material therein; of 90 means for imparting a reciprocatory movement thereto, said means comprising a slide, a rock member mounted upon a part independent of said slide, a cam connected with 95 said rock member, and elements connected with said slide and having contact with said cam; and means connected with said stop member for rotating the same in relation to said slide, said means comprising a handle connected with said stop member, and a 100 member connected with said slide for holding said handle in predetermined positions.

13. In a device of the character described, the combination with a stop member to limit the feed movement of material therein; of means for imparting a reciprocatory movement thereto, said means comprising a slide, a rock member mounted upon a part independent of said slide, a cam connected with 105 said rock member, and elements connected with said slide and having contact with said cam; and means connected with said stop member for rotating the same in relation to said slide, said means comprising a handle connected with said stop member, a member 110 connected with said slide for holding said handle in predetermined positions, and a spring member for holding said handle in engagement with said member.

14. In a device of the character described, 120 the combination with a feed stop for limiting the movement of material therein stationary in its stop position at the instant of contact of the material therewith, comprising in part a shaft with a stop finger fixed therein; of means for imparting a reciprocatory movement thereto, said means comprising a rock member; a cam connected with said rock 125

member; means for actuating said rock member, and an operative connection between said cam and said feed stop.

15. In mechanism of the character described, wherein material is fed therein and pieces successively cut therefrom, the combination therewith of means of limiting the feed movement of said material while the cut off mechanism is withdrawn stationary 5 in its stop position at the instant of contact of the material therewith, and comprising a shaft with a stop finger fixed thereon; and means for rotating said shaft to shift the position of said finger about the axis thereof.
- 15 16. In an upsetting machine or the like, wherein a rod is presented for an operation thereon; means for cutting off a projecting portion of said rod, whereby a blank is formed; a stop device for limiting the position of said rod before being cut off, actuated so as to first move into position to limit the movement of the end of the rod, then withdrawn to a point distant therefrom so as to clear the cut-off or other mechanism, 20 these movements of the stop device being in a line substantially parallel with the line of feed of said rod and means for moving said stop device in a path laterally to its line movement.
- 30 17. In a device of the character described, the combination with a power reciprocating shaft, of a stop finger connected therewith, means between the source of power for said shaft and said shaft, for determining the 35 length of movement of said shaft, and means associated with said shaft whereby it may be moved about its axis.
- 40 18. In a device of the character described, the combination with a power reciprocating shaft, of a stop finger connected therewith, means between the source of power for said shaft and said shaft, for determining the length of movement of said shaft, and means 45 associated with said shaft whereby it may be moved about its axis in any of its positions.
19. In mechanism of the character described wherein material is fed therein and

pieces successively cut therefrom, the combination therewith of means for limiting the feed movement of said material while the cut-off mechanism is withdrawn, stationary in the stop position at the instant of contact of the material therewith, and comprising a shaft with a stop thereon, means for imparting movement to said shaft in the direction of its length, and means for moving said shaft about its axis.

20. In mechanism of the character described wherein material is fed therein and pieces successively cut therefrom, the combination therewith of means for limiting the feed movement of said material while the cut-off mechanism is withdrawn, stationary in the stop position at the instant of contact of the material therewith, and comprising a shaft with a stop thereon, means for imparting movement to said shaft in the direction of its length, and means for moving said shaft about its axis, said means for moving said shaft about its axis and parallel to its length being operative at one and the same time.

21. In mechanism of the character described wherein material is fed at one place, pieces successively cut therefrom and transferred to another place, the combination therewith of means for limiting the movement of said material at its feed-in line while the cut-off and transfer mechanisms are withdrawn, comprising a shaft movable in a line substantially parallel with the path of movement of said material and in timed relation with said cut-off and transfer mechanism, and means for actuating said shaft from a power shaft, comprising an intermediate shaft mounted in a fixed part connected with the power shaft so that its position of rotation may be varied, and a member connected with said intermediate shaft and during its rotation contacting with parts associated with said shaft.

In testimony whereof I have hereunto affixed my signature.

RICHARD LESTER WILCOX.
